UNITED STATES PATENT OFFICE

2,476,161

SEWING-MACHINE THREAD CUTTER

Max Silverman, Forest Hills, N. Y.

Application September 29, 1947, Serial No. 776,707

4 Claims. (Cl. 112—252)

1

This invention relates to a sewing machine device for severing the threads at the termination of the sewed stitch, and its principal object is to provide an improved device for this purpose which will be conveniently and economically manufacturable, saleable at low cost, strong, durable, reliable, and conveniently and efficiently utilizable.

Another object is to provide an improved and efficient device for this purpose which will be conveniently installable upon the sewing machine, without requiring any mechanical alteration of the machine.

A further object is to provide an improved and efficient device for this purpose having means for its adjustment to cutting off of sewing threads of varying strengths and thicknesses.

Other objects and advantages will hereinafter appear.

In the accompanying drawings—

Fig. 1 is an elevational view of the sewing machine device constituting the invention, illustrating it as it appears when in operative installed state upon the machine.

Fig. 2 is a top plan view of the device shown in Fig. 1.

Fig. 3 is a transverse cross-sectional elevational view of the device, taken on line 3—3 of Fig. 2.

Fig. 4 is an elevational view of the device as it appears prior to installing it on the sewing machine, and as seen rearwardly of the view shown in Fig. 1.

The device 1 includes a metallic plate 2 having a flared end portion 3, and in its opposite end portion a hole 4, said plate carrying a projecting pin 5 and having a hole 6 between the pin and the end portion 3. Against the plate 2 is located a hard-metal plate 7 provided with a sharp cutting edge 8, and having a reversely flared end portion 9 with holes 10, 11 which register with the hole 6 and pin 5 respectively, the hole 11 being slidable over the pin 5. A screw 12 passes through the holes 6, 10 and threads through a nut 13 located against the cutter plate 7, and a spring 14 coiled around said screw bears against its head 12a and against the plate 2. The cutter plate 7 is thus mounted in place against the plate 2 and is guidable toward and away from the plate by the screw 12 and pin 5, while it is normally maintained in tensional contact with the plate 2 by the nut 13 which draws it to the plate by the action of the spring 14 against the screw head 12a. Threading of the screw 12 into and outwardly of the nut 13 varies the tension of the

2

spring 14 and therethrough the tensional contact of the cutter plate 7 with the plate 2.

The device 1 is installed on the sewing machine 15 by passing through the hole 4 the set screw 16 which secures the presser foot 17 to its operating rod 18, and tightening the screw 16 against the plate 2, in which manner the device 1 is firmly fastened to the presser foot 17 and disposed away therefrom and from the operative, as illustrated in Fig. 1. In operation of the device, the operative brings the sewing threads 19 emanating from the completed stitch into the bight of the flared portions 3, 9 and between the plates 2, 7, and severs said threads over the cutting edge 8 of the plate 7, the screw 12 having been previously adjusted to apply the desired tension between the said plates, in accordance with the strength or thickness of the used sewing threads 19.

20 Variations may be resorted to within the scope of the invention, and portions of the improvements may be used without others.

Having thus described my invention, I claim:

1. For a sewing machine embodying a presser foot, a rod for carrying said presser foot, and a screw securing the presser foot to said rod, of a thread cutting device having the combination of a member provided with a hole for therethrough passing said screw for securing the member to the presser foot, a cutter contacting with said member, said cutter and member having means to guide the cutter toward and away from the member, a spring drawing said cutter to said member, means to vary the tension of said spring, and the conjoint end portions of said cutter and member being flared to facilitate passing of the sewing thread between the cutter and the member and for severing of the thread by said cutter.

2. For a sewing machine embodying a presser foot, a rod for carrying said presser foot, and a screw securing the presser foot to said rod, of a thread cutting device having the combination of a member provided with a hole for therethrough passing said screw for securing the member to the presser foot, a cutter contacting with said member, a pin fixed to said member passing through said cutter to guide the cutter toward and away from said member, a screw passing through said member and cutter to additionally guide the cutter toward and away from the member carrying a nut against the cutter, a spring coiled around said screw drawing said nut to said cutter and the cutter against said member, the threading of said screw in said nut varying the tension of said spring and of the cutter against

said member, and said cutter and member having means to facilitate bringing the sewing thread between them.

3. A thread cutting device for a sewing machine having the combination of means for securing it to a sewing machine part, a member and a cutter contacting with each other, a pin fixed to said member passing through said cutter to guide the cutter toward and away from the member, a screw passing through said member and cutter to additionally guide the cutter toward and away from the member carrying a nut against the cutter, a spring coiled around said screw drawing said nut to said cutter and said cutter against said member, the threading of said screw in said member varying the tension of said spring and of the cutter against said member, and said member and cutter having means to facilitate bringing the sewing thread between them.

4. A thread cutting device comprising means for securing it in operative state, the device having a member and a cutter contacting with each

other, a pin carried by said member passing through said cutter to guide the cutter toward and away from the member, a screw passing through said member and cutter to additionally guide the cutter toward and away from the member carrying a nut against the cutter, a spring coiled around said screw drawing said nut to said cutter and said cutter against said member, the threading of said screw in said nut varying the tension of said spring and of the cutter against said member, and means to facilitate bringing the thread between the cutter and said member.

MAX SILVERMAN.
